United States Patent Office.

F. M. LEMMON, OF SHELBYVILLE, ILLINOIS.

Letters Patent No. 60,752, dated January 1, 1867.

IMPROVEMENT IN WHEEL-WRIGHTS' SPOKE-DRIVING BENCH.

The Schedule referred to in these Letters Patent and making part of the same.

TO ALL WHOM IT MAY CONCERN:

Be it known that I, F. M. LEMMON, of Shelbyville, in the county of Shelby, and State of Illinois, have invented a new and improved Spoke-Driving Bench; and I do hereby declare that the following is a full, clear, and exact description thereof, which will enable others skilled in the art to make and use the same, reference being had to the accompanying drawings, forming part of this specification, in which—

Figure 1 is a side view of my invention; and

Figure 2 is an end elevation of the same.

Similar letters of reference in the different figures indicate corresponding parts.

This invention relates to a new and improved machine for driving spokes in wagon-wheel hubs, and consists in a bench having a hub-clamping device by which the hub is firmly secured to the bench, and an adjustable rest for holding the spokes as they are driven, and also a binding device for holding the spokes down snug in the said rest as hereinafter explained, the whole making a very simple and desirable machine for the purpose mentioned.

B in the accompanying drawings is a bench of ordinary construction, having a bolt, D, passing up through its centre, the lower end of the bolt or rod D being hooked to the floor, and the upper end, d, having a screw-thread cut thereon and a nut, H, for clamping the hub A to the bench. C e is an adjustable rest which is adjusted vertically in the end of the bench by nuts I J above and below the same. G is a hooked rod for holding the spoke a down snug into the rest c, and this rod is operated by a lever, E, fig. 2, which is pivoted to the frame at e, and has a lip, f, which engages with a rack, F, to hold the lever in any position in which it is placed when in use. In driving the spokes the hub is first secured firmly on the bench by the clamping-rod D, and the height of the rest or gauge C is adjusted so as to give the desired set or "dish" to the wheel; the spoke a is then placed in position for driving, and the rod g G is hooked over the spoke, and the lever E forced down and engages with the rack F, to hold the spoke securely while being driven. After the spoke has been driven the hub is turned on the bench so as to bring another mortise opposite to the rest, and the operation is repeated until the spokes are all set. For accommodating larger wheels the hub-clamping rod D is placed farther from the rest in the hole b', fig. 1. By these means the spokes are properly set in the hub in a rapid and simple manner.

Having thus described my invention, what I claim as new, and desire to secure by Letters Patent, is—

I claim the bench B, clamping-rod D, adjustable rest C e, and holding-rod and lever G E, all arranged and operating as and for the purpose herein set forth.

F. M. LEMMON.
